[57] CLAIM

The ornamental design for a combined insulated food and beverage container, as shown and described.

DESCRIPTION

FIG. 1 is a top, front, and left side perspective view of a combined insulated food and beverage container showing my new design;

FIG. 2 is a top plan view thereof;

FIG. 3 is a front elevation view thereof;

FIG. 4 is a rear elevation view thereof;

FIG. 5 is a right side elevation view thereof, the left side being a mirror image of the right side as shown;

FIG. 6 is a perspective view thereof with the lid removed for illustrated purposes; and

FIG. 7 is a perspective view thereof of a second embodiment, the lid being the same as the first embodiment and removed for illustrated purposes only.

The undisclosed bottom view is plane and unornamented.

FIG. 1
